(57) **CLAIM**

The ornamental design for a torchiere floor lamp, as shown
and described.

DESCRIPTION

FIG. 1 is a perspective view thereof;

FIG. 2 is a front elevational view, all sides being identical;
and,

FIG. 3 is a top view thereof.

The broken line showing of environmental structure in
FIGS. 1-3 is for illustrative purposes only and forms no part
of the claimed design.

1 Claim, 3 Drawing Sheets

FIG. 1

FIG. 2

FIG. 3
